Primary Examiner — Bao-Yen T Nguyen(74) *Attorney, Agent, or Firm* — McAndrews Held & Malloy, Ltd.(57) **CLAIM**

The ornamental design for a display screen or portion thereof with a graphical user interface, as shown and described.

DESCRIPTION

1. Display screen or portion thereof with a graphical user interface

Front.

Fig. 1 is a front view of a display screen or portion thereof with a graphical user interface showing our design.

The outer edge of the portion of the display screen is understood to be congruent with the outer edge of the graphical user interface.
